UNITED STATES PATENT OFFICE.

ROBERT S. MOORE AND JAMES LEE SIMMONS, OF WASHINGTON, DISTRICT OF COLUMBIA, ASSIGNORS TO GYRO MOTOR COMPANY, OF WASHINGTON, DISTRICT OF COLUMBIA, A CORPORATION OF DELAWARE.

GAS-ENGINE.

1,022,864.

Specification of Letters Patent.

Patented Apr. 9, 1912.

Application filed November 1, 1910. Serial No. 590,237.

To all whom it may concern:

Be it known that we, ROBERT S. MOORE and JAMES LEE SIMMONS, citizens of the United States, residing at Washington, in 5 the District of Columbia, have invented certain new and useful Improvements in Gas-Engines, of which the following is a description, reference being had to the accompanying drawing, and to the letters and 10 figures of reference marked thereon.

The invention relates to new and useful improvements in gas engines and more especially to gas engines of the type wherein cylinders rotate about a stationary crank 15 shaft, although it is obvious that from certain aspects the invention is also adapted to be used in connection with an engine of the type wherein cylinders are stationary and the crank shaft rotates.

20 An object of the invention is to provide a valve and controlling mechanism therefor, for the intake or charging of the cylinder, which valve mechanism shall be of simple construction and of few parts, whereby the 25 weight of said mechanism is reduced to a minimum, and whereby there is less liability of the mechanism becoming inoperative or ineffective.

A further object of the invention is to 30 provide a four cycle multiple cylinder rotary cylinder gas engine with intake valves located in the pistons of the cylinder, together with mechanism controlled by the piston rod during the rotation of the cylinders for operating said valves.

These and other objects will in part be obvious, and will in part be hereinafter more fully described.

In the drawings which show by way of 40 illustration one embodiment of the invention; Figure 1 is a horizontal sectional view through a multiple cylinder engine embodying our invention. Fig. 2 is a vertical section through one of the cylinders and a portion 45 of the crank casing. Fig. 3 is an enlarged horizontal section through one of the cylinders and a portion of the crank casing. Fig. 4 is a detached end view of the oil guard.

50 We have shown our invention as applied to a multiple cylinder engine which is provided with a crank shaft 1, carrying a crank 2 to which is connected the piston rods 3

operating in connection with each cylinder. The crank shaft is preferably a stationary 55 crank shaft, and the casing 4, carrying the cylinders is rotated about said stationary crank shaft. It will be obvious however, that from certain aspects of the invention, the casing 4 may be stationary and the crank 60 shaft 1 rotated by the reciprocation of the pistons. Said casing 4 is herein shown as carrying five cylinders 5, 6, 7, 8, and 9. Each cylinder is provided with a piston 10 to which the piston rod 3 may be pivotally 65 connected in any desired way.

Located centrally of each piston head is an opening 11 in which is seated a valve 12. The valve 12 carries a stem 13 which extends through a suitable bearing 14 carried 70 by a cross support 15, which bridges the opening in the piston head and is connected to the piston head. A spring 16 surrounds the bearing 14 resting at one end against the cross support and at its other end against 75 a disk 17 attached to the stem of the valve. This spring will normally hold the valve seated in the opening in the piston head. The outer end of the piston 3 is provided with an enlarged head 18 which has a groove 80 or recess 19 extending transversely thereof. A cam finger 20 is pivoted at one end in said groove or recess 19, by a pivot bolt 21. A spring 22 is seated at one end in a socket 23 formed in the enlarged head 18 of the piston rod, and at its other end bears against the cam finger 20 normally holding the same raised as shown in Fig. 3. A suitable stop 85 may be provided for limiting the outward movement of the cam finger 20. Said cam 90 finger 20 has a cam shoulder 24 which is adapted to engage the outer rounded end 25 of the valve stem 13. As the cylinders rotate, the angle of the piston rod relative to the longitudinal axis of the cylinder is 95 varied and said variation or change in the angular position of the piston rod moves the cam shoulder 24 into and out of contact with the valve stem 13. As the cam 24 slides underneath the end of the valve stem, the 100 valve will be raised from its seat, to allow the intake from the crank casing. The spring 22 will however, yield so as to allow the valve to remain closed during the expansion of the gases in the cylinder. This is 105 accomplished by means of the fact that the

force of expansion of the gases overcomes the resistance of the spring 22 and causes the same to yield. The spring 22 is of course, normally of greater resistance than the 5 spring 16, so that when the cylinder is free from the expanding gases, the valve 12 will be opened by contact with the cam 24. The cylinder is provided with a suitable opening 27 in its outer end and an exhaust valve 26 10 is seated in said opening. Said exhaust valve is operated in the usual manner in a four cycle engine, so that said valve is opened during a portion of every other rotation of said cylinders.

15 In describing the operation of our device, the cylinder 6 in Fig. 1 may be considered as the second position of the cylinder 5, and the cylinder 7 considered the third position of the cylinder 5 and likewise for the cylinders 8 and 9. Starting with the cylinder 5 20 in the position shown in Fig. 1 and assuming that the gases in the cylinder are compressed and that the cylinder is at the firing position, the rotation of the cylinder to the 25 position of the cylinder 6 will bring the cam 24 into engagement with the lower end of the valve stem. Inasmuch as the gases in the cylinder are expanding and forcing the piston out of the cylinder, the valve will be 30 forced against its seat in the piston head and the spring 22 underneath the cam 20 compressed thus closing the cylinder to the intake from gas from the crank casing. The expansion of the gas continues as the 35 cylinder rotates to the position of the cylinder 7. When the cylinder passes the 180° point in its rotation, the angle of the piston rod will be changed relative to the cylinder and the cam 24 will be moved away from the 40 valve stem so that said valve stem is entirely free from contact with the cam during the remainder of the rotation of the cylinder.

The exhaust valve 26 is so timed that 45 after the cylinder passes the 180° point in its oscillation, the valve will be opened to allow the escape of the burned gases. The intake valve is closed as above noted and the rotation of the cylinder 5 to the position 50 shown in Fig. 3 will force the burned gases from the cylinder. The exhaust valve is now closed and as the cylinder continues its rotation, the intake valve 12 will be opened by the cam projection 24 during the rotation 55 of the cylinder through the next arc of 180°, and the gases in the crank chamber will pass through into the cylinder. The intake valve is then closed as the cam projection moves away from the valve stem and as the exhaust 60 valve is still held closed the completing of this rotation of the cylinder will compress the gases in the cylinder ready for the firing and for the next cycle of operation.

Another feature of our invention consists 65 in an oil guard which is attached to the pis-

ton for preventing the lubricating oil from passing through the piston into the cylinder. Said oil guard 30 is conical in shape, and provided with a closed end, which is slotted at 31 to allow the free movement of the pitman. The piston is also cut away at 28 and 29 so as to form spaced bearing surfaces for the piston, and allow the free passage of the lubricating oil from the crank casing to the wearing parts of the piston. These parts, however, are not claimed herein as they form the subject matter of a co-pending application Serial No. 590,236 filed concurrently herewith. 70 75

It is obvious that minor changes in the 80 details of construction may be made without departing from the spirit of our invention.

Having thus particularly described our invention, what we claim as new and desire to secure by Letters Patent, is:—

1. A gas engine including in combination a cylinder, a piston, an intake valve located in the piston, a piston rod connected to said piston, and means actuated by the piston rod for opening said intake valve, said means including a member capable of yielding so as to allow the intake valve to remain closed during the expansion of the gases in the cylinder. 85 90

2. A gas engine including in combination, a cylinder, a piston, an intake valve located in said piston, a piston rod connected to said piston, means carried by the piston rod for opening said intake valve, said means including a member capable of yielding so as to allow the intake valve to remain closed, during the expansion of the gases in the cylinder. 95 100

3. A gas engine including in combination, a cylinder, a piston, a piston rod connected to said piston, an intake valve mounted in said piston, a cam carried by said piston rod and adapted to engage said valve and open the same and means for supporting said cam whereby the same may yield so as to allow the intake valve to remain closed 105 during the expansion of the gases in the cylinder. 110

4. A gas engine including in combination, a cylinder, a piston, a piston rod connected to said piston, a valve mounted in said piston, a cam finger pivoted to said piston rod and adapted to engage said valve, and a spring for yieldingly holding said cam finger in operative position to engage said 115 valve. 120

5. A gas engine including in combination, a rotating casing, a cylinder carried thereby, a stationary crank shaft, a piston, a piston rod connecting said piston and said crank 125 shaft, an intake valve mounted in said piston, a cam carried by said piston rod for engaging said valve as the cylinder rotates, and means for supporting said cam whereby the same may yield to allow the intake 130

valve to remain closed during the expansion of the gases in the cylinder.

6. A gas engine including in combination, a rotating casing, a cylinder carried thereby, 5 a stationary crank shaft, a piston in said cylinder, a piston rod connecting said piston to said crank shaft, an intake valve mounted in said piston, a cam finger pivotally connected to said piston rod and having a projecting cam adapted to engage said valve as the cylinder rotates, and a spring 10 for yieldingly supporting said cam finger.

7. A gas engine including in combination, a rotary casing, a cylinder carried thereby, a 15 stationary crank shaft, a piston located in said cylinder, a piston rod connecting said piston to said crank shaft, said piston rod having an enlarged head with a recess formed therein, a cam finger pivoted in said recess in the piston rod, a cam projection carried by said finger for engaging the valve as the cylinder rotates, a spring seated at one end in said piston rod, and bearing its 20 other end against said cam finger for yield-

ingly holding the same in operative position.

8. A gas engine including in combination, a rotary casing, a cylinder carried thereby, an exhaust valve in the outer end of said cylinder, a piston mounted in said cylinder, a stationary crank shaft centrally through said casing, a piston rod connecting said crank shaft to said piston, said piston having an opening formed centrally thereof, a valve adapted to close said opening, a 30 spring for normally holding said valve seated, a cam finger carried by said piston rod for engaging said valve to open the same as the cylinder rotates, and a spring 35 for yieldingly supporting said cam finger.

In testimony whereof we affix our signatures in presence of two witnesses.
